SKYLIGHT CURB MEMBER

William Francis O'Keeffe, 75 Williams Ave.,
San Francisco, Calif.

Filed Nov. 13, 1963, Ser. No. 77,390

Term of patent 14 years

(Cl. D13—6)

FIG. 1.

FIG. 2.

FIG. 3.

FIG. 4.

FIG. 5.

FIG. 1 is a fragmentary perspective view of my new design for a skylight curb member;

FIG. 2 is a front elevation of the skylight curb member, the center thereof being broken away to indicate indeterminate length.

FIG. 3 is a rear elevation;

FIG. 4 is a top plan view; and

FIG. 5 is a bottom plan view.

I claim:

The ornamental design for a skylight curb member, as shown and described.
